DESIGN FOR AN ASTROLOGICAL MACHINE OR THE LIKE

Fairfield W. Hoban, New York, N. Y.

Application January 23, 1936, Serial No. 60,747

Term of patent 3½ years

To all whom it may concern:

Be it known that I, Fairfield W. Hoban, a citizen of the United States and a resident of the Borough of Manhattan, in the city, county, and State of New York, have invented a new, original, and ornamental Design for an Astrological Machine or the like, of which the following is a specification, reference being had to the accompanying drawing, forming a part thereof.

In the drawing:—

I claim:

The ornamental design for an astrological machine or the like, as shown.

FAIRFIELD W. HOBAN.
